UNITED STATES PATENT OFFICE.

JOHN W. HYATT, OF NEWARK, NEW JERSEY, ASSIGNOR OF ONE-HALF TO
DAVID BLAKE, OF NEWARK, NEW JERSEY.

MASSAGE INSTRUMENT.

SPECIFICATION forming part of Letters Patent No. 739,083, dated September 15, 1903.

Application filed January 26, 1903. Serial No. 140,484. (No model.)

To all whom it may concern:

Be it known that I, JOHN W. HYATT, a citizen of the United States, residing at 141 Commerce street, Newark, county of Essex, State of New Jersey, have invented certain new and useful Improvements in Reaction Massage Instruments, fully described and represented in the following specification and the accompanying drawings, forming a part of the same.

The object of the present invention is to furnish a massage instrument which is operated entirely by a reactionary force within its own shell, so as to require no attachment to auxiliary mechanism for vibrating the instrument.

The invention comprises a massage instrument having an external shell vibrated by the reaction of an unbalanced weight journaled within the shell. The rotating weight is connected to a flexible shaft or other suitable driver, and when the unbalanced weight is driven at a suitable speed it causes vibration of the shell by the direct reaction of the weight upon its journal. In the simplest form of the invention the shell is provided with a cylindrical bore and the weight is formed as a cylindrical plug fitted rotatably to said bore and provided at one side with one or more holes to throw it out of balance. The shell in such case is provided with heads to hold the revolving plug in place, and a spindle is extended from the plug through the center of one of the heads to attach a flexible shaft for driving the same. In this construction the bore of the shell operates as a bearing in which the entire plug is journaled; but the plug may be constructed to clear the interior of the shell and journaled to the heads, so that the reaction of the weight actuates the shell through the agency of the heads. The shell when made of cylindrical form may be grasped by the hand, so as to operate upon the hand itself; but the shell may also be made with a supporting-handle at one side and formed of any suitable shape for application by the handle to different parts of the body. The shell may in such case, if desired, be provided with a pad to fit the portion of the body upon which it is used.

Whether the shell be embraced by the hand or supported by a handle it is operated by the reactionary force of the weight and requires no connection with any auxiliary mechanism to produce the vibrations.

Heretofore massage instruments have been supported movably upon a holder which is sustained by an operator against whom the reaction of the instrument is exerted; but in the present invention the instrument requires no holder and no operator to sustain its reaction, but operates directly upon the part of the body with which it is in contact, and may thus be held and used by the patient without assistance.

The invention in several modified forms is shown in the annexed drawings, in which—

Figure 1 represents the shell grasped by the hand and connected with a flexible shaft. Fig. 2 is a longitudinal section of the same. Fig. 3 is a cross-section on line 3 3 in Fig. 2. Fig. 4 is a cross-section showing a rotatable plug with several holes, which may be filled to vary the operation of the plug. Fig. 5 is a longitudinal section of another alternative construction, and Fig. 6 shows the shell with an attached handle for applying it to various parts of the body.

Figs. 1, 2, and 3 show the shell of cylindrical form with the driving-spindle *b* projected from one end for connection with a flexible shaft *c*. The shell is of cylindrical form to be grasped by the hand, as shown in Fig. 1. To the cylindrical bore of the shell a cylindrical plug *d* is shown in Figs. 2 and 3, fitted rotatably and attached to the spindle *c*. The plug is shown with an eccentrically-disposed hole *e* extended through nearly its entire length, the metal of the plug being thus lightened upon one side, so that the weight is unbalanced when the plug is turned upon its axis by rotation within the shell. The plug is thus journaled to the bore of the shell and transmits the vibrations directly to the shell. Fig. 4 shows the plug formed with three holes *e*, *e'*, and *e''*, any of which may be filled by a plug *e'* to vary the center of gravity of the plug, and thus modify the vibrations when desired. Fig. 5 shows the plug with a hole *e* extended one-half its

length inward from one end and a hole e^4 extended one-half its length inward from the opposite end and the holes formed upon opposite sides of the plug, so as to unbalance the opposite ends upon opposite sides, and thus produce opposite vibrations of the shell at opposite ends of the same. The shell is shown in Fig. 2 threaded internally at opposite ends and the heads f and g screwed into the ends to hold the plug d in place. With the construction shown in Fig. 5 the spindle c is extended through both heads and is journaled therein, and the plug is made to clear the shell, so that its vibrations operate upon its bearings in the heads, and thus vibrate the shell. Fig. 6 shows a handle h extended from one side of the shell and the latter represented of greater diameter than length. It is obvious that as the diameter is increased the centrifugal force of the unbalanced weight is also increased, so that the vibrations of the shell may be suitably proportioning the shell and weight be adapted for operation upon different parts or organs of the body. The rotating weight, whether fitted to the bore of the shell or not, forms the vibrator of the instrument, and I have therefore termed the plug a "vibrator-plug" in the claims appended hereto.

It will be observed that this massage instrument requires only a single rotating part—namely, the unbalanced weight d —for connection with the driving-shaft c , and it thus differs essentially from all massage instruments which employ an eccentric crank or other analogous means located upon a supporting-frame and requiring connections to the massage instrument for vibrating the same in relation to and independently of such frame.

Having thus set forth the nature of the invention, what is claimed herein is—

1. A massage instrument having an external shell for contact with the body, an internal unbalanced weight journaled to the said

shell, and means for rotating the weight to vibrate the shell.

2. A massage instrument having an external shell for contact with the body, an unbalanced weight fitted rotatably to the inner surface of the shell, and means for rotating the weight to vibrate the shell.

3. A massage instrument having a shell provided with cylindrical bore, a vibrator fitted rotatably to said bore, and weighted upon one side as set forth, and means for rotating the weight to vibrate the shell.

4. A massage instrument having a shell provided with cylindrical bore, a vibrator-plug fitted rotatably to said bore, and provided at one side with one or more holes to throw it out of balance.

5. A massage instrument having a shell provided with cylindrical bore, a vibrator-plug fitted rotatably to said bore, and provided at one side with one or more holes to throw it out of balance, and means for filling any of said holes at pleasure to vary the center of gravity.

6. A massage instrument having a shell provided with cylindrical bore, a vibrator-plug fitted rotatably to said bore, and provided at opposite ends with holes upon opposite sides of its axis to produce opposed vibrations at the opposite ends of the shell, and means for rotating the plug within the shell.

7. A massage instrument having an external shell for contact with the body, an internal unbalanced weight journaled within the said shell, means for rotating the weight to vibrate the shell, and a handle attached to the shell for applying it to the body.

In testimony whereof I have hereunto set my hand in the presence of two subscribing witnesses.

JOHN W. HYATT.
